OIL CHANGE INDICATOR

Lewis L. Jones, Purvis, Miss.

Application March 11, 1952, Serial No. 275,950

1 Claim. (Cl. 116—114)

1. A device for indicating the necessity for changing the oil in a vehicle, comprising:

The present invention relates to an oil change indicator and it consists in the combinations, constructions and arrangements of parts herein described and claimed.

Generally there is provided an attachment for a conventional speedometer and consists of a device which is essentially a bell-crank lever, the upper arm of which is bent downwardly and is of sufficient width so that indicia such as "change of oil" may be placed thereon. When the arm is in a downward position this indicia is displayed through an opening cut into the face plate of the speedometer. The lower end of the lever is adapted to be moved rearwardly in order to cause the downward movement of the upper arms by means of a series of ten pins spaced equidistantly upon the outer periphery of the conventional speedometer cylinder which indicates thousands of miles. Hence as each new thousand miles is recorded by the speedometer itself, one of the pins will engage the lower arm of the bell-crank lever to cause the upper arm to display itself through the window above referred to. This indicates to the operator of the vehicle that it is time to change the oil in the vehicle. When he has noticed this state of affairs and wishes to reset the mechanism, it is only necessary to press a button also provided as a part of the invention and the inner end of the button is equipped with an arm which is adapted to move the upper arm of the bell crank mechanism rearwardly. A weight is attached to the upper arm so that the device becomes an over-center operating mechanism and will hence remain in either the indicating or not indicating position.

It is accordingly an object of the invention to provide a device of the character set forth which is simple in construction, inexpensive to manufacture and yet effective and efficient in use.

Another object of the invention is to provide a novel means for indicating the necessity for a change of oil in a vehicle, such means being automatic in operation.

Another object of the invention is to provide, in a device of the character set forth, novel means for resetting a mechanism as above described.

Other and further objects of the invention will become apparent from a reading of the following specification taken in conjunction with the drawing, in which:

Figure 1 is a front elevational view of an embodiment of the invention.

Figure 2 is a sectional view taken substantially along line 2—2 of Figure 1, and

Figure 3 is a sectional view taken substantially along line 3—3 of Figure 2.

Referring more particularly to the drawing, there is shown therein an automobile instrument panel 10 in which is mounted a conventional speedometer 11 equipped with a conventional face plate 12 and a window 13 through which is displayed a plurality of cylinders 14 to 19, inclusive, which represent, respectively, tenths of a mile, miles, tens of miles, hundreds of miles, thousands of miles and tens of thousands of miles.

The speedometer 11 is equipped with the conventional casing 20 into which extends the conventional cable housing 21 and other conventional mechanism generally indicated at 22 to operate the various conventional indicators in the speedometer 11. It will be noted that the cylinder 18 indicates thousands of miles. Accordingly, as a part of the present invention, there is provided ten radially extending circumferentially spaced pins 23 which extend from the cylinder 18. A bracket 24 is affixed to the rear face of the plate 12 by a screw 25 or the like and has pivotally mounted adjacent its rearward edge, as indicated at 26, a bell crank lever 27 which is provided with a lower arm 28 which normally lies in the path of movement of the pins 23.

The bell crank lever 27 is also provided with an upper arm 29 whose upper end is turned downwardly and forwardly as indicated at 30 whereby the same will come into close proximity with a window 31 which forms a part of the present invention and must be cut into the conventional face plate 12. The portion 30 is of sufficient width to bear indicia 32 such as "change oil" and is preferably colored with some attractive color such as red or yellow so that it will catch the eye of the operator of the vehicle in which the device is installed. Extending centrally and rearwardly from the main portion of the upper arm 29 is a weight 33.

In operation, it will be apparent that normally the bell crank lever will assume the position shown in full lines, for example in Figure 2 of the drawing, but that when the speedometer acts to indicate an additional thousand miles the cylinder 18 will be rotated in a counterclockwise direction as viewed in Figure 2 one-tenth of its circumference thus bringing one of the pins 23 into contact with the lower arm 28 of the bell crank lever 27 and thus causing the portion 30 to move downwardly into the dotted line position shown in Figure 2 thus bringing the indicia 32 into display through the window 31 thus indi-

cating to the operator of the vehicle that it is time for him to change his oil. In order to reset the device, so that the indicia 32 is not visible through the window 31, a lever 40 is provided which lever is hinged, as indicated at 41, to a bracket 43 mounted upon the rear side of the instrument 10. The arm 40 extends downwardly to a point adjacent the forward side of the portion 30 and is provided with a forwardly extending shaft 44 which extends through an opening 45 provided in the panel 10 and which terminates in a button 46. It will thus be seen that inward pressure upon the button 46 will cause the lower end of the lever 40 to impinge against the portion 30 of the bell crank lever to thus move the same rearwardly to its full line position as viewed again in Figure 2. It will also be apparent that the weight 33 will cause the lever 27 to be an over-center lever so that the lever will remain in either of the positions above described.

While but one form of the invention has been shown and described herein, it will be readily apparent to those skilled in the art that many minor modifications may be made without departing from the spirit of the invention or the scope of the appended claim.

What is claimed is:

A device of the character described comprising, in combination with a vehicle having an instrument panel and a conventional speedometer mounted therein, said speedometer including a casing, a face plate for said casing, a frame-

work in said casing, and total mileage indicator cylinders, the provision of means operable by one of said cylinders indicating when a change of oil is necessary for said vehicle, said means including a window in said face plate, a plurality of radially extending circumferentially spaced pins affixed to the outer periphery of said one cylinder, a bell crank lever pivoted to said framework and having an upper arm and a lower arm, said lower arm being in the path of movement of said pins, said upper arm being movable into and out of registry with said window and having indicia thereon visible through said window when said arm is in registry therewith, a weight attached to said upper arm for holding said upper arm upon either side of the pivotal point of said lever, a reset lever pivoted to the rear of said panel and adapted to move said upper arm out of registry with said window, a shaft affixed to said reset lever and extending through said panel, and a button affixed to the free end of said shaft.

LEWIS L. JONES.
